APPAREL BELT

Louis Krantz, New York, N. Y.

Application January 6, 1937, Serial No. 119,205

2 Claims. (Cl. 241—8)

This invention relates to improvements in apparel belts; and the invention has reference, more particularly, to that type of apparel belt which is constructed to permit of a compensating elastic stretch adapted to accommodate the same to bodily movements of the wearer.

An apparel belt which encircles the waist of the wearer must be fitted tightly enough to prevent sagging or slipping off of the garment to which it is applied for supporting effect, and its adjustment must be such that its maximum tightness accommodates the same to a snug fit about the waist when the wearer's body is quiet or relaxed. Under these conditions, when bodily movements occur, especially those of bending, stooping or those attendant upon walking, running and similar activity, a tight or snug fitting belt of unyielding character will not readily, if at all, accommodate itself to such body movements or to the muscular action involved, and as a result much discomfort to the wearer is engendered. To avoid these objections it has been proposed to provide apparel belts made in whole or in part of elastic or stretchable material, but belts of such elastic character have not heretofore given entire satisfaction, since the character and construction of the elastic material employed therein would soon wear and lose its elasticity or the power to recover normal initial condition after stretching. In most cases there was little resistance to stretch of the elastic material beyond its elastic limit, and consequently more or less rapid impairment and deterioration thereof ensued.

This invention has for its principal object to provide a construction of apparel belt having a novel longitudinally elastic body or body section made of a plurality of elastic cords having external sheaths of woven textile fabric; said sheathed cords being intertwined together by braiding or plaiting the same, or selected groups thereof, to thereby produce a body of braided or plaited formation. In such construction and formation of elastic body, the interengaging bights of the braided or plaited elastic cord frictionally contact one with another, and, when the body is submitted to longitudinal stretch, the braided or plaited cords tend to crowd together, whereby an effective resistance to stretch is increasingly set up which becomes proportionally greater as the limit of elasticity is approached. By reason of this, the novel elastic body, or body section, is sensitively responsive to initial stretching effect under bodily movements of the wearer accompanying normal activities, but nevertheless tends

to increasingly resist such stretching effect where the body movements are more violent or are of such character as to tend to elongate the body too nearly to the limit of its elasticity. By reason of this, the elastic body or body section is more efficiently resistant to wear, while at the same time it is nevertheless sufficiently responsive to ordinary bodily movements as to readily accommodate itself thereto at all times.

Another object of this invention is to provide a novel construction of apparel belt comprising connectible end strap section and a stretchable body section of braided elastic sheathed cords of the kind above mentioned; said end strap sections having buckle or like fastening means for releasably coupling the same together for fastening the belt about the body of the wearer.

Another object of the invention is to provide a belt or other apparel structure requiring an elastic section or sections, a longitudinally stretchable body of braided elastic cord as above mentioned which, in addition to its functional advantages, provides a neat, pleasing and attractive appearance adapted to enhance the value of the belt or other structure as an article of apparel.

Other objects of this invention, not at this time more particularly enumerated, will be understood from the following detailed description of the same.

An illustrative embodiment of this invention is shown in the accompanying drawing, in which—

Fig. 1 is a face or plan view of an apparel belt made according to the principles of this invention; Fig. 2 is a side edge elevation of the same; and Fig. 3 is a detail cross-sectional view, taken on line 3—3 in Fig. 1, but drawn on an enlarged scale.

Similar characters of reference are employed in the above described views, to indicate corresponding parts.

Referring to the drawing, the reference character 10 indicates one strap end portion of the belt and 11 the other strap end portion thereof. These strap end portions may be made of any suitable pliant but non-stretchable material, such as natural or artificial leather, woven textile fabric, or the like. One strap end portion, as 10, is provided with a buckle 12 connected with its free end. This buckle may be of any suitable mechanical construction adapted to receive and engage, in releasable coupled connection, the other strap end portion 11. Illustrative of one form of buckle which may be employed, I have shown the same to comprise a buckle of the harness type provided with a pivoted tongue or

prong 13 adapted to selectively engage through perforations 14 with which the strap end portion 11 is provided. Said strap end portion 10 is provided with the usual transverse loops 15 to receive and hold in flat lying position the free end part of strap end portion 11, when the latter is coupled to strap end portion 10 by means of the buckle 12.

Arranged between the strap end portions 10-11 is a body section of novel elastic or longitudinally stretchable character. This body section is produced from elastic cords 16 of rubber, which are each covered or sheathed in a tubular braided or woven covering 17 of textile material (see Fig. 3 more particularly). The sheathed elastic cords are intertwined and woven together by braiding or plaiting the same, to thus produce an elastic body section A of a width substantially corresponding to the widths of the strap end portions 10-11, between which said body section extends. The sheathed elastic cords may be braided singly or in multiples, i. e., in groups of selected number thereof. For example, as shown in the drawing, the sheathed cords are divided into groups of two each, and these groups are then braided or plaited together. When braided or plaited together, the sheathed elastic cords are criss-crossed and interwoven back and forth to extend over and under one another, thus obtaining a snubbed and frictional mutual engagement one with another at close intervals throughout the extent of the body section A formed thereby. Owing to this cross-crossed and snubbed frictional relation of the sheathed cords one to another, when the body section is submitted to elastic stretch, it will at first readily respond or yield to stretching effects, but as the stretching effect continues, with consequent progressive elongation of said body section, the mutually engaged bights of the interwoven sheathed cords will tend to crowd together, both in the direction of the width as well as in the direction of the thickness of the body section. Such crowding together will progressively increase the intensity of frictional engagement of the sheathed cords with consequent progressively increasing resistance to stretch. By such action any tendency of the body section to stretch beyond a reasonable elastic limit is quickly offset or arrested, and consequently the elastic efficiency or liveliness of the rubber constituent of the body section is conserved, and undue and rapid wear and tear of the body section in use is prevented.

The body section A is fixedly coupled by its ends to the adjoined ends of the strap end portions 10-11 by means of metal coupling clips B which surround, embrace and firmly clamp the adjoined ends of these parts, and thus couple said strap end portions and body section in a continuous unitary belt structure.

In addition to the described functional characteristics of the novel belt body section, it will be obvious that the same provides a very pleasing appearance calculated to enhance the eye appeal of the belt as a whole.

While I have described and desire to claim the novel elastic body section as incorporated in and constituting a functional part of an apparel belt structure, it will be apparent that the novel elastic body section per se is also adapted for use in other types of apparel supports, such as garters, suspenders, etc.

I am aware that some changes could be made in the above described structures, and that apparently widely different embodiments of this invention could be made without departing from the scope thereof. It is therefore intended that all matter contained in the above description or shown in the accompanying drawing shall be interpreted as illustrative and not in a limiting sense.

I claim:

1. An apparel belt, comprising non-stretchable strap end portions and an intermediate longitudinally stretchable body section, means to affix said strap end portions in connected end to end relation to said body section, said body section being composed solely of a plurality of elastic rubber cords, each cord being enclosed in a tubular braided fabric sheath, said sheathed cords being arranged in strands composed of a plurality of contiguous cords and said strands being interwoven into a braided formation with the mutually engaged cross bights of said strands disposed in frictional contact and adapted to crowd together with increasing resistance to stretch as the body section elongates toward the limit of its elasticity, and means to releasably couple the free extremities of said strap end portions in joined relation.

2. An apparel belt, comprising non-stretchable strap end portions and an intermediate longitudinally stretchable body section, means to affix said strap end portions in connected end to end relation to said body section, said body section being composed solely of a plurality of elastic rubber cords, each cord being enclosed in a tubular braided fabric sheath, said sheathed cords being disposed in multiple groups to form strands, said strands thereof being interwoven in criss-cross relation into a braided formation with mutually engaged cross bights in frictional contact and adapted to crowd together in both the directions of width and of thickness of the body section so as to offer increasing resistance to stretch as said body section elongates toward the limit of its elasticity, and means to releasably couple the free extremities of said strap end portions in joined relation.

LOUIS KRANTZ.
